PLASTER CAST CUTTER

Martin Merkur, New York, N. Y., assignor of one-third to Arnold Neustadter, New York, N. Y.

Application January 30, 1947, Serial No. 725,315

1 Claim. (Cl. 30—251)

1

This invention relates to a cutter for cutting and removing plaster casts.

In the removing of a plaster cast, it is desirable that the cast be removed with the least inconvenience or injury to the patient and that any pressure which may be necessary during the cutting of the cast be reduced to a minimum, if not entirely eliminated. It is, therefore, an object of this invention to provide a cast cutting tool which will not injure the patient and will cut the cast at the desired location.

Another object of this invention is to provide a cast cutting tool which will permit cutting of selected portions of the cast where such selected portions must be removed for any particular reason.

A further object of this invention is to provide a plaster cast cutter which will cut the cast in a neat and thorough manner without breaking or cracking the cast at undesired points.

With the above and other objects in view, my invention consists in the arrangement, combination and details of construction disclosed in the drawings and specification, and then more particularly pointed out in the appended claim.

In the drawings,

Figure 1 is a detail side elevation, partly broken away and in section, of a plaster cast cutter constructed according to an embodiment of this invention,

Figure 2 is a sectional view taken on the line 2—2 of Figure 1,

Figure 3 is a sectional view taken on the line 3—3 of Figure 1, with parts in the position indicated in dotted lines,

Figure 4 is a sectional view taken on the line 4—4 of Figure 1.

Referring to the drawing, the numeral 10 designates generally an elongated handle which is bifurcated at its forward end as indicated at 11 and 12. The handle 10 has fixed to the forward end thereof a stationary jaw 13, having a shank 14 engaging between the bifurcations 11 and 12, and secured therebetween by fastening means 15.

The jaw 13 is formed with a convex outer side 16 and with a substantially straight inner side 17 having a plurality of teeth 18 projecting therefrom. The jaw 13 is of tapered configuration in transverse section, as shown in Figure 3.

A movable jaw generally designated as 19 is pivotally mounted as at 20, on the shank 14 and disposed in a position for movement toward or away from the stationary jaw 13. The movable jaw 19 includes a pair of spaced blades 21 which are adapted to engage on the opposite sides of the

2

tapered portion of the jaw 13, as shown in Figure 3. The movable jaw 19 includes a pair of arms 22, engaging on the opposite sides of the shank 14, through which the pivot member 20 loosely engages. The movable jaw 19 also includes a substantially right angularly and rearwardly extending arm 23 which is pivotally connected by means of a pivot member 24 to the forward end of a second rockable handle or lever 25.

10 The handle or lever 25 is formed of obtusely related forward and rear parts 26 and 27. The movable handle or lever 25 is rockably connected to the stationary handle 10 by means of a link 28 pivotally secured as at 29, within an elongated 15 slot 30 formed in the handle 10. The opposite end of the link 28 is pivotally secured on a pivot 31 and is disposed in a slot or channel 32 formed in the inner side of the handle or lever 25. The movable handle or lever 25 is constantly urged to 20 jaw opening position by means of a spring 33 mounted on a pin 34 within the channel 32 and having one end portion thereof projecting into the channel 30 for engagement with a stationary pin 35 extending across the sides of the channel 25 or slot 30.

In the use and operation of this tool, the stationary jaw 13 is adapted to be inserted underneath the cast, the jaw 13 being of tapered configuration so that this jaw may be readily inserted beneath at least a small portion of the cast. After the jaw 13 has been inserted beneath the cast for a short distance, the handle or lever 25 may be rocked inwardly at its rear end, thereby swinging the movable jaw 19 forwardly so that the pair of cutting blades 21 carried by this jaw will cut through the cast which is also pierced between the blades 21 by the points or puncturing members 18. These points or puncturing members 18 also provide a means whereby the inner side of the cast is initially weakened along the line of the points 18 at the time initial pressure is applied to the jaw 19.

I do not mean to confine myself to the exact details of construction herein disclosed, but claim 45 all variations falling within the purview of the appended claim.

What I claim is:

A cutting tool comprising an elongated handle, a stationary jaw carried by one end of and disposed at right angles to said handle, said jaw including a cutting edge having a plurality of rearwardly directed article puncturing points, a movable jaw including a pair of spaced blades adapted to straddle said cutting edge, means 50 rockably mounting said movable jaw on said
